UNITED STATES PATENT OFFICE.

HERBERT A. PARKYN, OF CHICAGO, ILLINOIS.

REFRIGERATING APPARATUS.

1,405,319.

Specification of Letters Patent. Patented Jan. 31, 1922.

Application filed February 27, 1919. Serial No. 279,579.

To all whom it may concern:

Be it known that I, HERBERT A. PARKYN, a citizen of the United States, residing at Chicago, in the county of Cook and State of Illinois, have invented a new and useful Improvement in Refrigerating Apparatus, of which the following is a specification.

My invention relates, more particularly, to improvements in refrigerating apparatus of the type employing a compressor for compressing the gasified refrigerant, such as ethyl chloride or sulphur dioxide, after leaving the refrigerating expansion coil; and condensing means in communication 15 with the compressor for reducing the compressed refrigerant to liquefied condition.

One of my objects is to provide a simple and economical arrangement for the cooling of the compressed refrigerant by the 20 use of air alone, to place it in the desired condition for introduction into the refrigerating coil. Another object is to provide a closed air-circuit refrigerating system which will be simple and economical of 25 construction and compact, and shall be relatively inexpensive to operate. Another object is to provide a refrigerating unit, more especially for domestic use, which may be furnished as a unit with all of the parts 30 of the refrigerating apparatus in fixed operative positions, for ready application to refrigerators or ice boxes, as commonly provided, without requiring more than the cutting of openings in a wall of the box, the 35 refrigerating apparatus extending entirely exterior of the box, to the end that not only shall the box serve in a highly effective manner as a refrigerating means, but the space usually occupied by the ice may be 40 utilized as storage space for material, such as food stuff, to be cooled.

Referring to the accompanying drawings, Fig. 1 is a view in vertical sectional elevation of an ice box of common form with my 45 improved refrigerating unit applied thereto; Fig. 2 is a section taken at the line 2—2 on Fig. 1 and viewed in the direction of the arrows; Figures 3 and 4 are sections taken at the lines 3—3 and 4—4 and viewed 50 in the directions of the respective arrows; and Fig. 5, a section taken at the line 5 on Fig. 1 and viewed in the direction of the arrow.

In accordance with the preferred, illustrated, embodiment of my invention shown 55 as provided for application to a common

form of ice-box of the single, air-circuit variety, namely, one involving the introduction of cold air at one side of the box, its passage downwardly and across to the opposite side of the box, and its discharge from the box at the last-referred-to side, I provide a base 10 which, in the form shown, is a hollow metal member affording the chambers 11 and 12, this base being provided 60 preferably for application to the top of the ice-box to which it is to be applied, where the invention is provided for application to ice-boxes built to employ ice as the refrigerating medium. 70

The base 10 supports the operating parts of the refrigerating apparatus which, in the case of the air-cooled machine illustrated, comprises the following described elements: a driving element represented at 13, and 75 which, by preference, is an electric motor, the armature shaft of which, represented at 13^a, is directly connected with the compressor, represented at 14, and which, by preference, is of the intermeshing-gear type, 80 the compressor being located in a chamber 15 containing an oil bath 16, in which the compressor is submerged, the outlet of the compressor, and which is represented at 17, discharging into the compressor chamber 15, 85 the outlet 15^a of which is connected with one end of a condensing coil 18. The coil 18 is located in a casing 19, in which the compressor chamber 15 is located, this coil being in the form of an open spiral located 90 between the wall of the casing 19 and an annular, concentrically disposed, partition 20 in the latter and surrounding the chamber 15. The discharge end of the coil 18 leads into a liquefied refrigerant receiver 95 21 located in the chamber 12 in the base 10 and held in place by a strap 22 secured to the base, with insulating material, represented at 23, surrounding the receiver 21. The apparatus shown also involves a refrigerating coil 24 located in the chamber 11 in the base, this coil being connected at one 100 end with an expansion valve 25 in communication with the receptacle 21, and at its opposite, discharge-end 26 leading into 105 the inlet of the compressor 14.

The shaft 13^a is provided with a fan 27 and with a blower 28, both rigidly secured to this shaft. The fan 27 is located in an opening 29 in the casing 19 and serves to 110 draw air through this opening and force it through the spaces between the various

turns of the condenser coil 18, from which it flows upwardly in the casing 19 and thence downwardly on the inside of the partition 20 and out through openings 30 in the base of the compressor-chamber 15, and into the base 10 through an opening 31 therein and out to the atmosphere through the opening 32 in this base, air being thus caused to flow against the coil 18 and compressor chamber 15 and operating to cool these parts, with the result of aiding in the condensing of the compressed refrigerant. The blower 28 may be of any suitable construction. As shown, it is composed of the vane-equipped member 33, fixed on the shaft 13^a, and a casing 34, having double walls spaced apart with insulation 35 therebetween, mounted on the base 10, the casing 34 being connected at its inlet 36 with the warm-air return of the refrigerator-box, and at its outlet 37 opening into the chamber 11 in the base 10 to discharge the warm air against the refrigerating coil 24.

The compressor of the particular apparatus illustrated involves a plurality of intermeshing gears 38 and 39 mounted on the shaft 13^a and the shaft 40, respectively, which are journaled in the casing 41 of the compressor, this casing having a gas-inlet port at one end, in communication with the outlet 26 of the refrigerating coil 24, and in communication with a channel 42 in the casing 41, and extending lengthwise of the gears 38 and 39 and opening into the intermeshing portions thereof at one side of the centers of the shafts 13^a and 40, the outlet 17 of the compressor and represented at 43 being in communication (in a manner not shown) with the intermeshing portions of the gears 38 and 39 at the ends of the latter at the side of the centers of the shafts 13^a and 40 opposite that at which the channel 42 extends. By preference the pipe 17 extends above the level of the oil bath 16, this bath affording a supply of lubricant through the oil inlets 41^a in the casing 41, to the intermeshing gears to lubricate these parts and produce an oil-seal, as is known in the art.

The space 11 in which the coil 24 is located is preferably lined with insulation 45, the upper portion of the space 11 containing an opening 46 communicating with the outlet 37 of the lower casing 34, and its lower end containing an outlet 47, through which the air drawn from the ice-box into the inlet 36 of the blower and thence cooled by contact with the coil 24, discharges.

In the installing of the apparatus for use in connection with ice-boxes built for use with ice as a refrigerating medium, openings forming passageways, are cut in the cover of the box for registration with the outlet of the chamber 11 and the inlet of the blower, these openings in the cover of the box communicating with the portion thereof in-

tended to receive the ice, and with the warm-air return, respectively. In the particular arrangement shown the refrigerating unit is applied to a common form of ice-box represented at 100 and having a single warm-air return and in accordance with this arrangement the top 101 of the box has openings 48 and 49 cut therein to register with the outlet 47 and inlet 36, respectively, these openings being preferably lined by pipe sections 50 and 51, respectively. The openings 48 are located in the top of the ice-chamber portion 102 of the box and the openings 49 are located in the top of the warm-air-return portion of the box.

In the operation of the structure, as shown, the compressor 14, driven by the motor 13, compresses the gasified refrigerant entering it through the pipe 26 from the coil 24, discharging it into the compressor chamber 15, from whence it passes into the condenser coil 18, wherein it condenses and thence flows as a liquid into the receiver 21, the liquified refrigerant discharging into the refrigerating coil 24 through the expansion valve 25 in accordance with common practice. The fan 27 simultaneously driven with the compressor and at a rapid speed, by reason of its direct connection with the shaft 13^a, operates to enhance the cooling of the compressed gasified refrigerant in its passage through the compressor chamber 15 and coil 18, the rotation of this fan on the shaft of the rotary compressor and motor being at such speed that the desired cooling effect for causing the apparatus to continuously operate under widely varying temperature conditions, is effected. Furthermore, the mounting of the rotary element 33 of the blower directly on the shaft 13^a causes this element to be rotated at relatively great speed for effecting the maximum cooling action of a predetermined volume of air circulating through a closed system, the warm air being drawn upwardly through the lefthand side of the refrigerator and the cold air being discharged into the upper portion of the righthand side thereof, the course traveled by the air in passing through the box being indicated by the arrows in Fig. 1.

If desired, the chamber 11 may be used for the making of ice cubes, the structure shown to this end being provided with a drawer 52 carrying a series of square chambers 53 for receiving water and being slideable in and out upon guides 54 in this chamber, through an opening 55 in the front wall thereof, these guides being located within the confines of the coil 24.

While I have illustrated and described a particular construction embodying my invention, I do not wish to be understood as intending to limit it thereto, as the same may be variously modified and altered with-

out departing from the spirit of the invention, it being my intention to claim my invention as fully and completely as the prior state of the art will permit.

5 What I regard as new and desire to secure by Letters Patent is:

1. A refrigerating unit adapted to be used with a refrigerator box having an opening therethrough communicating with the portion of the air-circulation course thereof through which the cold air passes, and comprising a base, a compressor and driving means therefor on said base, a condenser and refrigerating coil on said base, said unit 10 containing a passage exterior of said box and communicating with said opening for conveying air into a position where it will be cooled by said refrigerating coil and pass thence through said opening into the 15 box, and a power-device for forcing the air through said passage.

2. A refrigerating unit adapted to be used with a refrigerating box having openings therethrough communicating, respectively, 20 with the portions of the air-circulation course thereof through which the cold air and warm air passes, and comprising a base, a compressor and driving means therefor on said base, a condenser and refrigerating coil 25 on said base, said unit containing a passage exterior of said box for communication at its opposite ends, respectively, with the said openings in the box, said passage being so arranged relative to said refrigerating 30 coil that air in traversing said passage will be cooled by said coil, and means in said passage for effecting forced circulation of the air therethrough.

3. A refrigerating unit adapted to be used 35 with a refrigerator box and comprising a base, a compressor and driving means therefor on said base, a condenser on said base, said base containing a passage for air, a refrigerating coil located in said passage, and 40 means for forcing air through said passage to produce a forced circulation.

4. In refrigerating apparatus, the combination of a rotary pump for compressing the gasified refrigerant, a shaft connected therewith, a motor directly connected with said 45 shaft for driving it, a condenser for the

compressed by said pump, a refrigerating coil in communication with said condenser, and a blower on said shaft for forcing air into a position where it will be cooled by 55 said refrigerating coil.

5. In a refrigerating system, the combination of a rotary pump for compressing the gasified refrigerant, a shaft connected therewith, a motor directly connected with 60 said shaft for driving it, a condenser for the gas compressed by said pump, a fan on said shaft for causing air to be driven against said condenser, a refrigerating coil connected with said condenser, and a blower on said 65 shaft for forcing air into a position where it will be cooled by said refrigerating coil.

6. In refrigerating apparatus, the combination with a refrigeration chest enveloped by a heat-insulating medium, of a passage 70 located exteriorly of said chest and opening at its ends through said insulating medium into the interior of said chest at different points therein and forming a connection exterior of said chest between the warm- 75 air portion of the chest and the cold-air portion thereof, whereby a closed air-circulating course is provided, artificial refrigerating means located exteriorly of said chest and said insulating material and arranged to cool the air in said closed course, and means in said passage for producing forced circulation of the air through said closed course.

7. In refrigerating apparatus, the combination with a refrigeration chest enveloped 80 by a heat-insulating medium, of a passage located exteriorly of said chest and opening at its ends through said insulating medium into the interior of said chest at different points therein and forming a connection exterior of said chest between the warm-air portion of the chest and the cold-air portion thereof, whereby a closed air-circulating course is provided, artificial refrigerating means located exteriorly of 85 said chest and said insulating material and arranged to cool the air in said closed course, a blower in said passage for producing forced circulation through said course, and a power-device for operating said blower, 90 located exteriorly of said course.

HERBERT A. PARKYN.
